Filed Jan. 31, 1973, Ser. No. 328,308

Term of patent 14 years

Int. Cl. D7—04

U.S. Cl. D7—47

FIG. 1 is a front elevational view of a food grater embodying my new design;

FIG. 2 is a top plan view thereof;

FIG. 3 is a cross-sectional view taken along the line 3—3 of FIG. 1; and

FIG. 4 is a cross-sectional view taken along the line 4—4 of FIG. 1.

The rear elevational view is the same as the front elevational view shown in FIG. 1. The bottom of the food grater is flat.

I claim:

The ornamental design for a food grater, as shown and described.
